(57) **CLAIM**

The ornamental design for a foldable grabber reacher, as shown and described.

DESCRIPTION

FIG. 1 is a front, right and top perspective view of a foldable grabber reacher, showing our design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1 comprising a sphere.

FIG. 10 is a partial enlarged view of an area labeled 10 in FIG. 2 comprising a plurality of grooves; and,

FIG. 11 is another front, right and top perspective view of the foldable grabber reacher of FIG. 1 in a folding status. The rods of the foldable grabber reacher are shown with a symbolic break in their length. The appearance of any portion of the foldable grabber reacher between the break lines forms no part of the claimed design.

The broken lines in the drawings depict portions of the foldable grabber reacher that form no part of the claimed design. In addition, the dot-dash broken lines in the drawings illustrate an enlarged portion of the design.
